UNITED STATES PATENT OFFICE.

HENRY B. CORNISH, OF LIVERPOOL, ENGLAND.

ELECTRIC SWITCH.

1,420,472.

Specification of Letters Patent. Patented June 20, 1922.

Application filed March 8, 1922. Serial No. 542,018.

To all whom it may concern:

Be it known that I, HENRY BEDFORD CORNISH, subject of the King of Great Britain, residing in Liverpool, in the county of Lancaster and Kingdom of England, have invented certain new and useful Improvements in and Relating to Electric Switches, of which the following is a specification.

The present invention relates to improvements in electric switches.

According to the present invention an electric switch comprises a bar which passes through radial perforations in a pair of cylindrical contacts or terminals between which the circuit is to be broken.

This bar is for switching purposes displaceable either as a rotation about its own axis or in the direction of its axis, and preferably has cam surfaces on it engaging with a radial spring plunger to obtain a snap action.

The invention is more particularly described with reference to the accompanying drawings in which:—

25 Figure 1 is a sectional elevation showing the invention applied to a pear switch by way of example.

Figure 2 is a sectional view on an enlarged scale of a switch bar,

30 Figure 3 is a view on an enlarged scale of a terminal piece,

Figure 4 is a sectional view on an enlarged scale of the snap action pin and its spring, whilst,

35 Figure 5 is an elevational view on a slightly enlarged scale of the partition carrying the contacts.

The device comprises a body 1, shown in the present example as being the top of a 40 pear switch. It is obvious that it may equally well be a body of any other electric fitting such as a wall switch or the like. This body 1 has a closing cap 2, of usual form which is provided with a loose partition piece 3, notched at 4, to allow for the passage of the switch bar 5. This switch bar has one end formed of insulating material, whilst the other end 6 is of metal and has an operating knob 7 at its outer end. This 45 switch bar 5 passes through perforations 8 in the terminal piece 9. These terminal pieces are embedded in a mass of insulating material such as porcelain, ebonite or the like forming the partition 3. The terminal 50 pieces may be provided with the usual perforations and screw connections for the con-

ductors 10 or may be perforated as at 11, so that the conductors can be threaded therethrough, the free end of the conductor being passed through the groove 12, arranged at 60 right angles to the perforation 11, and through the open groove 13, arranged diametrically across the end of the terminal piece. It will be found that connections of this kind will not allow the conductors 10 65 to pull away from the terminal pieces 9. As an additional precaution the partition may be provided with the bridge 14 of usual construction having grooves 15 for the reception of the conductors 10.

70 The centre of the switch bar in the form illustrated has a double conical attachment 16, adapted to co-operate with a pin 17 mounted in a socket in the partition 10, and pressed upwards by a spring 18. It will consequently be seen that as the switch bar 5 is pressed either to one side or the other, contact will be made from one terminal piece 9 through the flange 19 of the switch bar to the part 6, of this and then to the other 80 terminal piece 9, whilst in the other position the circuit is interrupted by reason of the insulating portion of the switch bar 5 coming within one of the terminal pieces 9, the switch bar being held locked in either position by means of the spring pin 17 which 85 will produce a snap action.

I declare that what I claim is:—

1. An electric switch comprising a base, a switch bar formed of conducting and non-conducting parts, a pair of terminal pieces on said base perforated at their ends to receive said switch bar, means to displace the switch bar through said perforated terminal pieces so that conducting or non-conducting 95 parts respectively connect said terminals.

2. An electric switch comprising a base, a switch bar formed of conducting and non-conducting parts, a pair of terminal pieces on said base perforated at their ends to receive said switch bar, means to displace the switch bar through said perforated terminal pieces so that conducting or non-conducting parts respectively connect said terminals, a cam abutment on said bar and a spring plunger connected with said cam abutment to provide a snap action.

3. An electric switch comprising a base, a switch bar formed of conducting and non-conducting parts, a pair of terminal pieces 110 on said base perforated at their ends to receive said switch bar, means to displace the

switch bar through said perforated terminal pieces so that conducting or non-conducting parts respectively connect said terminals, a double conical abutment on said switch bar and a spring plunger connecting therewith to provide a snap action.

In witness whereof, I have hereunto signed

my name this 20th day of February 1922, in the presence of two subscribing witnesses.

H. B. CORNISH.

Witnesses:

JAMES C. MCRAE,
HENRY J. GREGORY.
